UNITED STATES PATENT OFFICE

CARLOS H. BOWLEN, OF HAVERHILL, MASSACHUSETTS, ASSIGNOR TO IRVING L. KEITH,
OF HAVERHILL, MASSACHUSETTS

CEMENTING MACHINE

Application filed November 6, 1929. Serial No. 405,117.

This invention relates to cementing machines which are primarily designed for use in cementing sock linings to the bottoms of shoes, and particularly to machines of the type disclosed in my prior Patent #1,565,004, dated December 8, 1925.

While machines constructed as illustrated in my said prior patent operate satisfactorily in cementing sock linings in shoes of certain types, in certain other types of shoes, and more particularly those having high heels, considerable difficulty has been encountered in performing this work satisfactorily, for the reason that transverse wrinkles or pockets are liable to be formed in the lining between the transverse strips of adhesive which are applied by the bars. That is, the uncemented portions of the lining between the cemented strips are not held in close contact with the shoe bottom, but tend to rise up from the bottom in ridges. This difficulty is not likely to occur in the heel and foreparts of the bottom, or in the rear portion of the shank part, but is particularly likely to occur in the front portion of the shank part closely adjacent the ball line, at which line the shoe if it carries a high heel, is bent so sharply that a relatively deep transverse concavity is formed, which is often deeper in the middle portion than at the sides of the shoe.

The object of my present invention is to provide a form of grid which will apply the cement to the heel and forepart of the lining in substantially the same manner as disclosed in said patent and will enable these portions to be secured in position in a manner which is satisfactory, and which will also apply the cement to the shank portion in such a manner that the lining when inserted in the shoe, and pressed against the bottom, will be held closely to the bottom surface throughout, so that no wrinkles or pockets will be formed between the por-

tions which are adhesively connected and those which are not.

I accomplish this object by providing the grid with a series of transverse bars which are so arranged that transverse stripes of cement will be applied to the heel and foreparts, as in my said prior construction, and with intermediate longitudinal bars, so that longitudinal stripes of cement will be applied to the shank part of the lining or portions adjacent the ball part thereof.

For a more complete disclosure of the invention, reference is made to the following specification in connection with the accompanying drawings in which:

Fig. 1 is a plan view of a cementing grid embodying my invention.

Fig. 2 is a transverse section thereof, at line 2—2 of Fig. 1 and

Fig. 3 is a side elevation thereof.

The grid herein disclosed is supported, operated and in a general way constructed, identically as disclosed in my said patent and comprises end hangers *a* between which parallel supporting rods *b* are extended, means being provided for holding said rods horizontally and for lowering the same into a cement pan and for lifting it above the liquid level.

A parallel series of suitably spaced, transversely disposed cementing bars *c*, *d* are mounted on the end portions of the rods *b*, a sufficient number thereof being provided to form a cementing surface at each end of the grid which extends lengthwise of the grid a distance approximately as great as the length of the forepart of any sock lining which is likely to be placed thereon. The bars shown are preferably of the zig-zag type, although they may be straight, or otherwise formed, and their top edges are longitudinally convex, the structure being, as thus far referred to, substantially the same as in my said prior patent.

According to my present invention, a pair

of flat bars *e* are mounted on the side rods *b* in close proximity to the bars *c* and *d* which are next adjacent each other, and a parallel series of round bars, or stiff wires *f* are mounted at their ends in the bars *e*. The top edges of the bars *e* are longitudinally convex and their top edges lie in the same curved surface as that of the top edges of the bars *c*, *d*. Also the holes, or recesses in the bars *e*, in which the round bars *f* are mounted, are formed close to the top edges thereof, so that the surfaces of the round bars are practically tangent to the same curved surface as that in which the top edges of the other bars lie.

In using the device for cementing sock linings, the grid will be submerged in liquid cement and then lifted above the level thereof, and then the lining will be placed lengthwise of the grid in such a position that its shank portion rests on the longitudinal bars *f* and its forepart rests on one of the sets of transverse bars *c* or *d*, the heel part resting on the other set of transverse bars, approximately as indicated in Fig. 1.

As a result of this operation transversely extending stripes of cement will be applied to the fore and heel parts of the lining and longitudinally extending stripes of cement will be applied to the shank portion thereof, said stripes conforming to the formation of the grid portion to which the lining is applied. In practice, some or all of the longitudinal stripes will preferably extend for a short distance across what is usually considered as the ball-line, so that, when the lining has been placed in position in the shoe and pressed into contact with the shoe bottom throughout its entire surface, by means of a brush or other means, this operation being performed in the manner described in said prior patent, the lining will be adhesively connected to the shoe bottom throughout its entire surface, and the portion of the lining adjacent the ball line will be connected by stripes of cement which extend longitudinally of the shoe, or transversely of the concave portion formed by the bend at the front end of the shank. As these stripes of cement thus run crosswise of this concavity, the lining will be connected to the shoe bottom along these stripes and the formation of transverse wrinkles or pockets in the lining will be prevented, the uncemented portions being held flat on the shoe bottom. The other portions of the lining will be effectively attached by the transverse stripes of adhesive, the shank portion in the rear of the concave portion at the ball being as effectively held by the longitudinal, as by the transverse stripes of cement. It will be understood that if the linings were always to be placed on the grid with the toe end at the same end of the grid, the bar arrangement would probably be

changed somewhat from the arrangement shown, but it is desirable to be able to place the lining on the grid with the toe portion at either end, so that the arrangement shown is considered to be the more advantageous.

It will be understood that the particular types of bars shown are not essential to the invention, although they are preferable.

I claim:

1. A grid for applying a liquid adhesive to sock linings of shoes comprising two series of adjacently disposed bars, the bars of both series having adhesive applying faces at their top sides all disposed in approximately the same surface, the bars of one of said series being arranged for engagement with the forepart of the lining and the bars of the other series being arranged for engagement with the portion of the lining at and adjacent the line at which its shank part meets the forepart, the bars of the latter series being arranged to extend in transverse relation to said line to apply the adhesive to such portion in stripes which extend longitudinally of the lining.

2. A grid for applying a liquid adhesive to sock linings of shoes comprising two series of adjacently disposed bars, the bars of both series having adhesive applying faces at their top sides all disposed in approximately the same surface, the bars of one of said series being arranged for engagement with the forepart of the lining in transverse relation thereto and the bars of the other series being arranged in transverse relation to the fore part engaging bars and in position to engage the portion of the lining adjacent the junction of the shank and forepart of the lining and to apply adhesive to such portion to stripes which extend lengthwise of the lining.

3. An elongated grid for applying liquid adhesive to sock linings of shoes comprising two series of adjacently disposed bars having adhesive applying faces at their top sides arranged to provide a transversely convex cementing surface, the bars of one of said series being arranged transversely of the grid and the bars of the other series being arranged longitudinally thereof, each bar of the longitudinal series being terminated in close proximity to the side of the adjacent bar of the transverse series.

4. An elongated grid for applying liquid adhesive to sock linings of shoes comprising two series of transversely disposed bars arranged at the opposite ends of the grid and an intermediate series of longitudinally extending bars terminating at the sides of the adjacent transverse bars, all of said bars having adhesive applying faces at their top sides arranged to provide an adhesive applying surface adapted to receive the fore part of the lining on one of said transverse

series of bars and the shank part thereon on said longitudinal series of bars.

5. An elongated grid for applying liquid adhesive to sock linings of shoes comprising two series of transversely disposed bars arranged at the opposite ends of the grid and an intermediate series of longitudinally extending bars mounted at their ends in the adjacent transverse bars, all of said bars
10 having adhesive applying surfaces arranged for simultaneous engagement with the lining when placed thereon.

In testimony whereof, I have signed my name to this specification.
